UNITED STATES PATENT OFFICE

99,590

DESIGN FOR A SALT BLOCK

Albert H. Torongo, New Rochelle, N. Y., assignor to General Foods Corporation, New York, N. Y., a corporation of Delaware

Application March 20, 1936, Serial No. 61,705

Term of patent 14 years

To all whom it may concern:

Be it known that I, Albert H. Torongo, a citizen of the United States, residing at New Rochelle, county of Westchester, State of New York, have invented a new, original, and ornamental Design for a Salt Block, of which the following is a specification, reference being had to the accompanying drawing forming part thereof.

Figs. 1, 2, and 3 are end, side, and perspective views, respectively, of a salt block showing the design.

I claim:

The ornamental design for a salt block, as shown.

ALBERT H. TORONGO.
